G. L. HOGAN.

VAPOR BURNING APPARATUS.

APPLICATION FILED JULY 30, 1914.

1,158,687.

Patented Nov. 2, 1915.

UNITED STATES PATENT OFFICE.

GEORGE LEWIS HOGAN, OF CHICAGO, ILLINOIS, ASSIGNOR, BY DIRECT AND MESNE ASSIGNMENTS, TO KEROSENE UTILITIES COMPANY, A CORPORATION OF ILLINOIS.

VAPOR-BURNING APPARATUS.

1,158,687.

Specification of Letters Patent.

Patented Nov. 2, 1915.

Application filed July 30, 1914. Serial No. 854,085.

To all whom it may concern:

Be it known that I, GEORGE LEWIS HOGAN, a citizen of the United States, residing at Chicago, in the county of Cook and State of Illinois, have invented a new and useful Vapor-Burning Apparatus, of which the following is a specification.

My invention relates to improvements in vapor-burning apparatus in which a container, or containers, for the liquids to be vaporized, work in conjunction with a tubular vaporizing burner.

The object of my invention is to provide a simplified vapor-burning apparatus with means of preventing such apparatus from clogging by deposits of carbon and foreign matter. I attain this object by the structure illustrated in the accompanying drawings in which,

20 Figure 1 is a perspective view of the entire apparatus in operative position. Fig. 2 is a side view of the liquid containers and their support, showing a part sectional view. Fig. 3 is a sectional view on the line 3—3 25 Fig. 2. Fig. 4 is a cross section of the tank N on the line 4—4 Fig. 2. Fig. 5 is a cross section of the tank supporting mechanism on the line 5—5 Fig. 2. Fig. 6 is a sectional view of the vapor generating and burning mechanism on the line 6—6 Fig. 1. Fig. 7 is a sectional view of the vapor generating and burning mechanism on the line 7—7 Fig. 6. Fig. 8 is a sectional view of the same on the line 8—8 Fig. 6. Fig. 9 is a 30 part sectional view on the line 9—9 Fig. 6.

35 Similar letters refer to similar parts throughout the several views.

N is a tank for holding a hydrocarbon liquid or fuel supply such as kerosene oil.

40 U is a tank for holding a hydro-oxygen cleaning solution such as water, or, preferably, a mixture of water and alcohol. These two tanks are each in operative relation through a common flexible conducting tube

45 M with the vapor generating and burning mechanism at the valve D. A valve W is placed in the conducting passage 28 connecting the tank U with the common conducting tube M so that either of the tanks, U and

50 N, may be brought into operative relation with the vaporizing and burning apparatus independent of the other. The tank N is provided with a strainer S through which its liquid has to pass before entering the 55 tank proper.

10—11—12—13 are spring clasps for the purpose of holding in position a piece of finely woven cloth such as silk, should it be desired to strain the oil or liquid through silk.

63 The tank N is provided with one or more bearings 15—16 Fig. 2 with holes in them to slide freely up and down on a guide rod Z, which guide rod is supported by the fittings T—K. The fitting T is provided with a projection containing a pocket 17 Fig. 5, into which pocket the supporting projection 15 fits when the tank N is in proper position for working. The fittings T—K are fastened to a board Y, which board is intended 65 to be nailed to the wall or otherwise supported at an elevation above the vaporizing and burning mechanism D—X—A—P—L. The tanks N and U are fastened together at 30—31 but have no interior connection except through their respective valves O and W and conducting tube 28—14, and the tube 14 is made to project upward above the bottom of the tank N, as in Fig. 2, for the purpose of forming a trap in the bottom 70 of such tank into which sediment will sink, preventing its entering the tube 14, and passing to the burner, or clogging the tube M. The tanks U and N may be lowered for the purpose of filling by lifting the tank N until 75 its supporting projection 15 clears its pocket 17 Fig. 5 and then swinging it around the guide rod Z until the projection 15 clears fitting T and allows the bearings 15—16 to slide down the rod Z when the bearing 16 80 will rest on the fitting K and support the mechanism until filled, when it may be raised back into its upper support.

85 Q is a common connection or junction of the tube 28 from the valve O of the tank N 90 and the common conducting flexible tube M connecting with the valve D of the vaporizing and burning mechanism.

95 The vaporizing and burning mechanism comprises a valve D, a threaded pipe 22, a pair of locknuts 25—26, a casting C with an opening 31 in its front portion through which the pipe 22 passes and to which it is firmly supported by the locknuts 25—26; a coupling V, a pipe 21, a pipe X, a pipe 35, 100 and connections 33—34 and a hollow fitting A, plugged at the end J, all fastened together in a gas-tight manner to form a vaporizing chamber, but with a hole 36 drilled through the fitting A connecting with 105 110

its interior hollow portion which hole 36 serves as an outlet for oil and vapor or gases at the different stages of operation.

P is an adjustable baffle plate with a circular motion about the central pivoted hinges 18-19. Such motion is controlled by a rod R, loosely fastened at 20, at its one end, and projecting through a hole 32 in the front portion of the casting C at the other end. This allows adjustment of position and direction of deflection of the vapor as it forces its way through the outlet hole 36 of the fitting A and is burned. By pulling the rod outward the plane of the baffle plate P will incline more upward and deflect the flame of the burning vapor in a more vertical direction, and by pushing the rod R inward the flame will assume a more horizontal position, thus admitting of a very useful control or means of concentrating the heat where required.

The baffle plate P is removably held to the pivoted member 37 by a screw 27 to enable it to be easily replaced if and when required, and to permit of its being of a more fireproof material than is required for its supporting member 37.

A lighting pan L is attached to the fitting A by a supporting rod 39 and the pan L is filled or partly filled with asbestos 38 for the purpose of absorbing an inflammable liquid to be lighted to impart the initial heat required to start the mechanism to vaporizing, which is best accomplished by opening the valves O and D until enough of the inflammable liquid from the tank N passes through the tube M to the outlet 36 and drops into the pan L underneath and then to close the valve D and light the absorbed liquid in L which will soon heat the liquid in A to the temperature of vaporization, when the vapor will forcibly rise against the baffle plate P and ignite the flame from L, which latter flame will disappear as soon as it has consumed all of the oil absorbed by the asbestos 38. The initial heat having thus been attained, the valve D may be again opened and left open until it is desired to stop the operation of the device, when it may be closed. The casting C is provided with a screw rod F, with a hole 23 diametrically through its central portion for the purpose of inserting a rod to be used as a wrench or lever for the purpose of screwing it in or out of the casting C in such manner that the pressure of its foot I on the bottom of the door opening of the furnace and the top portion of C on the top of the furnace door opening will hold the entire vaporizing and burning mechanism in position by friction, thus preventing the necessity of drilling or riveting and effecting a simple method of quickly fixing the mechanism into any furnace.

H represents a skeleton door intended to

slip over and hang on the casting front C to cover the space not filled in by such casting when placed in the door opening of the furnace.

During the decomposition of the hydro-carbon oil being vaporized from the tank N, a small deposit of carbon will form in the vaporizing chamber or the pipes 21-X-35, and the fitting A and hole 36. This formation is caused from there not being proper elements inside such pipes during this vaporization to combine with the carbon set free to form carbonaceous gases. To remove this deposit of carbon the valve W is opened while the fire is burning and all parts of the vaporizing mechanism are hot and any deposit of carbon therein is also hot. A few drops of the water, or mixture of water and alcohol, of the tank U is allowed to pass the valve W and make its way to the burner and the valve W is then closed. As soon as the water is exposed to the heat it vaporizes and chemical combination takes place with it and the deposit of heated carbon, forming both hydrocarbon gas and carbonic acid gas, which also increases the pressure and blows with great force through the outlet 36, thoroughly cleaning it, and thus removing the carbon by chemical combination, which is one of the principal features of my invention, and without which no oil burner can be relied upon as practical.

I claim as new:

1. An apparatus for vaporizing and burning hydro-carbon liquids comprising a source of fuel supply in operative relation with a vaporizing chamber provided with an outlet for burning the said vapor, and a hinged angular baffle plate imposed above such outlet, having a free lateral movement about its axis at a point below the vapor outlet, and a controller rod attached to the said baffle plate at one end and the other end extending out through the front portion of the burner forming a handle of a lateral movement for the purpose of adjusting such baffle plate.

2. An apparatus for vaporizing and burning hydro-carbon liquids comprising a source of fuel supply, a vaporizing chamber consisting of a tube or series of tubes, means for conducting fuel from said source to said vaporizing chamber, a suitable frame for supporting such tubes, and a screw rod in such frame, so arranged that by adjustment such rod may be made to engage a portion of the opening into which such apparatus is to be attached by pressure and force the said frame against the opposite portion of such opening, thereby clamping the said frame firmly within said opening, and means for clamping the said vaporizing chamber into the said frame, such vaporizing chamber being provided with an orifice or open-

ing and a baffle plate imposed above such orifice, substantially as and for the purpose described.

3. An apparatus for vaporizing and burning hydro-carbon liquids comprising a source of fuel supply, a vaporizing chamber consisting of a tube or series of tubes, means for conducting fuel from said source to said vaporizing chamber, a suitable frame for supporting such tubes, a screw rod in such frame so arranged that by adjustment such rod may be made to engage a portion of the opening into which such apparatus is to be attached by pressure and force the said frame against the opposite portion of such opening, thereby clamping the said frame firmly within such opening, a sheet

metal door to fit over such frame in such manner as to substantially close the space of such opening not occupied by such frame, 20 means for clamping the said vaporizing chamber into the said frame, such vaporizing chamber being provided with an orifice, a hinged baffle plate imposed above such orifice, and a controlling rod attached at its 25 one end to such baffle plate and passing through the said frame at its other end so as to form a handle; substantially as and for the purpose described.

GEORGE LEWIS HOGAN.
